Inventor,

G. F. Meacham

United States Patent Office.

GEORGE F. MEACHAM, OF NEWTON, ASSIGNOR TO JAMES W. TUFTS, OF MEDFORD, MASSACHUSETTS.

Design No. 4,768, dated April 4, 1871.

DESIGN FOR SODA-FOUNTAINS.

The Schedule referred to in these Letters Patent and making part of the same.

To all whom it may concern:

Be it known that I, **GEORGE F. MEACHAM**, of Newton, in the county of Middlesex and State of Massachusetts, have invented and produced a new and original Design for the Casing of a Soda-Water Apparatus, of which the following is a full, clear, and exact description, reference being had to the accompanying photographs making part of this specification.

In the photographs—

A represents the casing of a soda-water apparatus, the lower portion or base *b* of which is of rectangular form, while the portion above the base is made in the form of an eight-sided polygon, the design thus produced being unique and ornamental.

Claim.

What I claim as my invention, and desire to secure by Letters Patent, is—

The design for the casing of a soda-water apparatus, herein shown and described.

Witness my hand this 8th day of March, A. D. 1871.

GEO. F. MEACHAM.
